UNITED STATES PATENT OFFICE

VICTOR J. SIGODA, OF BROOKLYN, NEW YORK

HEMSTITCH ATTACHMENT FOR SEWING MACHINES

Application filed August 19, 1929. Serial No. 386,837.

The present invention relates to hemstitch sewing machines, and has for its main object the provision of an improved gathering device, the invention being in the nature of a novel attachment produced especially for use in connection with the Singer type of machines, such for instance, as Nos. 72w19 and 72w20, although it is to be understood that the attachment is not confined to that particular type or to such particular make of machines.

An important object of the invention is the provision of an attachment of the character described, which will gather and group the fibers or strands of the material into a zigzag or serpentine hemstitch pattern, and one in connection with which the needles of the machine, functioning in the usual manner, will cooperate to stitch the grouped fibers or strands both on the right and left sides, to produce a permanent hemstitch of a zigzag or serpentine pattern.

A further object of the invention is the provision of an attachment of the character described for ornamenting, bordering, or hemming fabric with a zigzag or serpentine hemstitch, in contradistinction to the cross hemstitch now generally used.

A further object of the invention is the provision of an improved attachment having improved means for piercing and grouping the fibers or strands of the fabric.

With the foregoing objects and others in view, the invention resides in the forms and details of construction and in novelties of combination and arrangement, as will be hereinafter more fully described, illustrated in the accompanying drawings, and particularly pointed out in the subjoined claims.

For a full understanding of the invention reference is to be had to the accompanying drawings, which form a material part of this application and in which

Figure 1 represents a fragmentary perspective view showing a hemstitch sewing machine equipped with my improved attachment;

Figs. 2, 3 and 4 represent detail views on a large scale, of the attachment;

Fig. 5 represents a cross section on the line 5—5 of Fig. 2;

Fig. 6 represents an exaggerated plan view of the zigzag or serpentine hemstitch pattern produced by the attachment; and

Fig. 7 represents a view similar to Fig. 6, but showing a modification in the design of the pattern.

Referring first to the well-known parts of the Singer machine, No. 72w19, fractionally illustrated in Fig. 1 of the accompanying drawings, the numerals 10 designate the needle holders, 11 the needles, 12 the needle vibrating levers, 13 the needle vibrating lever screws, and 14 denotes the presser foot, 15 the presser foot holder and 16 the piercer holder.

In this assembly the attachment of my invention is denoted generally at 17 and is shown as attached to the usual piercer holder 16 for cooperation with the needles 11 in the same way as the usual piercer employed in connection with this type of sewing machine. By those familiar with the art, it will be understood that the conventional piercer (not shown), which is applied to the holder 16, produces the cross hemstitch pattern now generally used. My new attachment 17, designed to pierce the fabric, gather a group of the fibers and form them into an oblique hemstitch course for the production of a zigzag or serpentine pattern, has a standard stem 18 so that it may be applied to the piercer holder 16 in place of and in substitution for the usual piercer.

Although having in practice, as above intimated, the three-fold function of piercing the fabric, gathering fibers and placing them into oblique groups, my attachment 17 may, for convenience of reference, be hereinafter referred to simply as a gathering device.

The preferred form of construction of the gathering device 17, as illustrated in Figs. 1 to 5, inclusive, comprises right and left elongated parts or blades 19 which are formed or otherwise produced on the forwardly offset lower end portion 20 of the standard stem 18. The two blades 19 are separated by an elongated slot 21 having a flaring gate or mouth opening 22 formed be-

tween the oppositely directed piercing points 23.

For a portion of their length, the inner edges of the elongated blades, defining the slot 21, are rounded as at 24, both at the front and rear faces of the blades. Between the piercing points and the points of their union with the stem portion 20, the bodies of the blades 19 are expanded or enlarged as shown 10 in a plane of symmetry transversely to the direction of feed of the work or fabric, the outer edges 25 of the blades forming substantially a convex curve, curving inwardly in an upward direction toward the stem union, and inwardly in an upward direction to the piercing points 23. The outer edges 25 of the blades are provided with grooves or pockets 26 for the proper operation of the needles 11.

20 As is well known in the art, in order to hemstitch the fabric, a group of the fibers or strands as 27, where the hemstitching is to take place, is withdrawn or pulled from the transversely extending fibers or strands 28, which intersect the fibers or strands 27, at right angles. By thus withdrawing successively a series of fibers as 27, only the transversely extending fibers 28 remain. The fabric is placed in sewing position under the 25 presser foot and fed in a direction away from the operator with the transverse fibers 28, upon which the device 17 operates directly, positioned transversely to the line of feed of the work. The stitching mechanism including the needles 11 operates in the usual manner to produce the right and left lines of stitching 29 and 30 with the lock stitches 31 and 32 in the line of stitching and with the lock stitches 33 laterally offset relatively 30 to the line of stitching. The attachment 17 periodically penetrates the work, dividing out, gathering and positioning the groups of fibers in advance of the production of the lock stitches by which the groups of fibers 45 are tied in place.

According to an important feature of the invention, the piercing point on one of the blades curves forwardly toward the operator while the piercing point of the other of the blades curves rearwardly away from the operator.

Manifestly, by this arrangement, when the device descends two depth perforations are made in advance of the needles with the result that a group of the transverse fibers is engaged between the two penetrating points to slip through the mouth opening 22 into the elongated opening 21 and thence onto the rounded inner edges 24. As a result of this 55 operation, the gathered group of transverse fibers 28 are formed into an obliquely extending course 34. Each time the device descends, it divides out and gathers between the prospective lines of stitching a group of 60 fibers and positions them in a course 34 ex-

tending obliquely to the direction of feed of the fabric, and the course 34 is held between the blades until the needles tie the lock stitches 31 and 32 at either end thereof; it being observed that the lock stitches embrace 70 not only the particular divided out course, but also a diverging or oppositely inclined course 34' which results from the dividing out of the next succeeding course 34. Owing to the shape of the blades, to the gathering of the fibers in courses obliquely to the line of feed, and as well to the binding effect of the lock stitches and especially of the laterally offset lock stitches 33, the repetition of the courses 34 and 34' results in the formation 80 of a zigzag or serpentine pattern.

As illustrated in the modification shown in Fig. 7, one or more of the fibers or strands 27 may remain unpulled in the longitudinal central region between the prospective lines 85 of stitches 29 and 30. By leaving these unpulled fibers or strands in the central region, the two blades of the descending device during the formation of the oblique courses, straddle these fibers or strands without substantially altering their position, so that in this case the completed serpentine hemstitch will have a longitudinally extending central course connecting the courses 34 and 34'.

It will be apparent from the foregoing 95 description, taken in connection with the accompanying drawings, that I have produced a novel and useful hemstitch attachment which embodies the features of advantage enumerated in the statement of invention and the above description; and while I have, in the present instance, shown and described in detail a preferred embodiment thereof, it is to be understood that it is susceptible of modification in various particulars without 100 departing from the spirit or scope of my invention or sacrificing any of its advantages.

I claim:

1. In a hemstitch sewing machine, embodying stitch forming mechanism including 110 right and left needles for producing right and left courses of stitching in the direction of the feed of the work, and a gathering device coacting with the needles, its construction including blades having piercing points 115 curving in opposite directions for forming in advance of the stitching, groups of fibers, so disposed relative to each other as to produce a serpentine hemstitch pattern.

2. In a hemstitch sewing machine, embodying stitch forming mechanism including 120 right and left needles for producing right and left courses of stitching in the direction of the feed of the work, a gathering device coacting with the needles and adapted to form in advance of the stitching, inclined groups of fibers, said gathering device including right and left piercing blades the piercing points of which are bent in opposite directions with respect to each other to gather. 125

and form between the blades, on each piercing operation, an inclined group of fibers.

3. In a hemstitch sewing machine, embodying stitch forming mechanism including right and left needles for producing right and left courses of stitching, a gathering device cooperating with the needles to gather a group of fibers between the paths of the needles and in advance of the stitching, said gathering device comprising right and left blades with a space between them, said blades having piercing points curving in opposite directions so as to gather between them a group of fibers for entry into said space, to be retained in said space by said blades while being stitched at the right and left in the right and left courses of stitching performed by said needles.

4. In a hemstitch sewing machine, embodying stitch forming mechanism including right and left needles for producing right and left courses of stitching in the direction of the feed of the work, a gathering device cooperating with the needles to form in advance of the stitching, groups of fibers, obliquely inclined with respect to the direction of travel of the work, said gathering device comprising right and left blades the bodies of which lie in a plane transverse to the direction of travel of the work, and said blades having piercing points bent in opposite directions.

5. In a hemstitch sewing machine, embodying stitch forming mechanism including right and left needles for producing right and left courses of stitching in the direction of the feed of the work, a gathering device cooperating with the needles to form in advance of the stitching, groups of fibers, obliquely inclined with respect to the direction of travel of the work, said gathering device comprising right and left blades the bodies of which lie in a plane transverse to the direction of the travel of the work, and piercing points on said blades bent forwardly and backwardly to gather and feed a group of fibers obliquely between the bodies of the blades so as to be secured by the two courses of stitching.

6. An attachment for hemstitch sewing machines for the purpose set forth, comprising a stem for connection with the piercer holder, two piercing blades united at their upper ends to the stem and otherwise separated, the bodies of the blades being enlarged in a plane of symmetry and narrowing to piercing points curving in opposite directions, said points being adapted, when piercing fabric, to gather fibers between them at an angle to the plane of symmetry and to direct the gathered fibers between said blades.

7. An attachment for hemstitch sewing machines for the purpose set forth, comprising a stem for connection with the piercer

holder, two piercing blades united at their upper ends to the stem and otherwise separated, said blades having piercing points and expanding bodies between the piercing points and the union with said stem, the piercing points being curved in opposite directions from the bodies so as to gather, when piercing fabric, a group of fibers between them and to direct the received group between the bodies to be there positioned at an angle with respect to the plane of enlargement of the bodies.

8. An attachment for hemstitch sewing machines for the purpose set forth, comprising a pair of blades connected at their upper ends and otherwise separated, said blades having piercing points curving in opposite directions and adapted, when piercing fabric, to receive a group of fibers between them and direct the received group between said blades.

9. An attachment for hemstitch sewing machines for the purpose set forth, comprising a pair of blades connected at their upper ends and having an elongated space between them, said blades having piercing points curving in opposite directions and adapted, when piercing fabric, to receive between them courses of fabric intersecting at right angles and to direct said courses between the blades, the bodies of the blades being formed to position one of the intersecting courses at an oblique angle with respect to the other of the intersecting courses.

10. An article of manufacture, a gathering device of the character described comprising a stem, a pair of elongated blades connected at one end to the stem and having an elongated opening between them, and piercing points on said blades curving in opposite directions and forming a gate opening to said elongated opening.

In testimony that I claim the foregoing as my invention, I have signed my name hereto.

VICTOR J. SIGODA.
